UNITED STATES PATENT OFFICE.

MARK E. FERNALD, OF SAUGUS, MASSACHUSETTS, ASSIGNOR TO C. C. BLAKE,
INCORPORATED, OF BOSTON, MASSACHUSETTS, A CORPORATION OF NEW
YORK.

METHOD OF MAKING CUTTING DIES.

1,403,238.

Specification of Letters Patent. Patented Jan. 10, 1922.

Application filed October 1, 1915. Serial No. 53,640.

To all whom it may concern:

Be it known that I, MARK E. FERNALD, a citizen of the United States, residing at Saugus, in the county of Essex and State of 5 Massachusetts, have invented a new and useful Improvement in Methods of Making Cutting Dies, of which the following is a specification.

The present invention relates to methods 10 for making cutting dies which are used to dink out irregular shapes from sheet material.

Heretofore these cutting dies have been hand-forged which is an expensive and laborious operation requiring the services of a skilled operative.

The object of the present invention is to provide a simple, cheap and effective method by means of which cutting dies may be manufactured without the employment of skilled labor.

To the accomplishment of this object, and the production of a novel cutting die, the features of the invention relate to certain 25 methods, devices, combinations and arrangements of parts hereinafter described and then set forth broadly and in detail in the appended claim which possess advantages readily apparent to those skilled in the art.

30 The various features of the present invention will be readily understood from an inspection of the accompanying drawings showing the best method of practising the invention at present known to the inventor, in which,

40 Figure 1 is a plan of the blank for the casting pattern, for casting the cutting die, provided with a flange which is built upon the blank by winding a strip of paper in layers on the edge thereof;

Fig. 2 is a sectional elevation of the blank shown in Figure 1;

Fig. 3 is an elevation, partly in section, of 45 a machine for imparting a draft to the flange of the casting pattern;

Fig. 4 is a sectional elevation of the finished casting pattern;

Fig. 5 is a plan of the cutting die; and

Fig. 6 is a sectional elevation of the cutting die.

Describing now in general terms my novel method of making cutting dies the first step consists in the production of a flat blank for the foundation of a casting pattern for

casting the cutting die. This blank is substantially the same size and shape as the sole to be cut out of the hide by the finished cutting die. The sole-shaped blank 1 is then inserted into the machine described in application for Letters Patent of the United States filed by me October 27, 1914, Serial No. 868,921. This machine is provided with a rotatable support for the blank; devices for supporting, guiding and feeding a strip of material, such as paper; and a pair of rolls for attaching the paper to the peripheral edge of the blank and winding the paper in layers thereon. To build the guiding flange the rolls are mounted upon a carrier which tips automatically as the point of operation of the rolls is transferred around the reverse curves of the blank to maintain the rolls substantially normal to the point of operation. This carrier is mounted on a swinging support which swings automatically 70 during the rotation of the blank to permit the rolls to travel around the toe and heel portions of the blank and reach the shank portions thereof. The machine is also provided with a feed accelerator which imparts an automatic pull to the supply end of the paper so that the paper may be attached to the shank portions of the blank while the paper is free from tension. After the pattern is completed by this machine the 75 draft necessary for the removal of the pattern from the sand is imparted to the pattern by a second machine which is disclosed in application for Letters Patent of the United States filed by Charles C. Blake, October 29, 1914, Serial No. 869,336, to which reference is made by permission. This machine is provided with a series of rolls which simultaneously support, guide, feed and operate automatically upon the pattern to im-

part the draft thereto and remove any roughness on the top and bottom faces of the flange. After the pattern has been removed from this machine the surplus stock upon the exterior face of the flange at the lower 80 end thereof is removed and a fillet of beeswax is placed in the angles at the junctures of the flange and the body portion of the blank in order to prevent the molder's sand from lodging in the cracks at these points. The pattern is then finished by providing it with a coat of shellac. The casting pattern thus produced is utilized in the casting for

105

the cutting die. After being removed from the sand the flange on the casting is ground on its exterior face at the lower end thereof to form the cutting edge of the die.

- 5 Referring to the drawings the sole-shaped blank 1 is provided with a laminated flange 2 which has been built upon the blank by winding a strip of paper in layers around the peripheral edge thereof. In order to 10 impart the draft to the flange necessary for the removal of the casting pattern from the molder's sand and to smooth the irregularities on the top and bottom faces of the flange the pattern is passed through a machine provided with a series of rolls which support, 15 guide, feed and operate automatically upon the pattern as it passes through the machine. As shown in Figure 3 these rolls comprise a 20 pair of rolls 3 and 4 which engage the top and bottom faces of the body portion of the pattern respectively and which are also constructed and arranged to engage the inner faces of the flange and impart the draft thereto, a pair of rolls 5 and 6 which engage the top and bottom faces of the flange 25 respectively and smooth the irregularities thereon, and a fifth roll 7 which engages the outer face of the flange and imparts the draft thereto.
- 30 After the draft has been imparted to the pattern the pattern is first dried and then the surplus material upon the exterior face of the flange at the lower end thereof is removed as shown at 8 (Fig. 4). A fillet of beeswax 9 is then placed in the angles at the junctures of the flange 2 and body portion 1 (Fig. 4) in order to prevent the molder's sand from lodging in the cracks

at these points. The pattern is then finished by providing it with a coat of shellac. 40

The finished casting pattern is then utilized in the casting of the cutting die which comprises a body portion 10 having a peripheral flange 11. Upon its removal from the sand the flange 11 of the cutting die is 45 ground upon its exterior face at the lower end thereof to form the cutting edge 12.

While the illustrated embodiment of the present invention is directed to the manufacture of a cutting die for use in cutting soles 50 from hides or other sheet material, it will be apparent to those skilled in the art that the methods herein disclosed may be advantageously employed in making other kinds of cutting dies.

55 The operations which are performed as above described and illustrated are those which are preferred in practising the present invention, it is to be understood, however, that except as defined in the claim 60 the invention is not limited to the precise methods illustrated and described and that the steps of the method may be varied or modified without departing from the spirit of the invention.

65 What is claimed as new is:—

That improvement in the art of making cutting dies which consists in producing a blank, building a flange upon the edge of the blank, imparting a draft to the flange, 70 removing surplus stock from the exterior face of the flange at the lower end thereof, and utilizing the product of the four steps recited as a casting pattern for casting the cutting die.

MARK E. FERNALD.
